UNITED STATES PATENT OFFICE.

MARTIN D. GOURLAY, OF CLAREMONT, NEW HAMPSHIRE.

LOOM.

Application filed January 28, 1924. Serial No. 689,074.

My invention relates to looms.

It has for its object to provide an improved loom adapted to produce an improved fabric adapted to various uses, but especially adapted to use in bed spreads or the like, having an improved textile structure of warp and weft threads wherein the same warp and weft threads form both the ground and the design woven therein and wherein the design assumes any desired form and the leno is woven independently in any desired form and without necessary repetition across the fabric. A more specific object of my invention is to provide an improved mechanism for weaving such a fabric having improved slackener mechanism adapted to produce the latter, and, more particularly, an improved loom mechanism of the jacquard type whereby through the control of the slack in the warp in an improved manner and by improved means, the above results may be obtained more satisfactorily, conveniently, simply and cheaply and without substantial change in a standard Jacquard loom. These and other objects and advantages of my improvement will herein-after more fully appear.

In the accompanying drawings I have shown for purposes of illustration one embodiment which my invention may assume in practice, showing a jacquard mechanism for producing a bed spread fabric, which will be first considered, and thereafter certain illustrations of the fabric.

In these drawings,

Fig. 1 is a partial vertical sectional view of a jacquard mechanism equipped with my improvement.

Fig. 2 is a diagrammatic view partially in plan and side elevation showing one series of warp threads and my improved mechanism for acting upon the same.

Fig. 3 shows enlarged detail views in side and front elevation, of the working end of a warp slackener.

Fig. 4 is a detail plan view of a part of the warp ends with a plurality of slack adjusters acting thereon.

Fig. 5 is a diagrammatic plan view of a completed spread formed of my improved fabric.

Fig. 6 is an enlarged diagrammatic view showing the structure of a portion of a selected form of fabric.

In this illustrative disclosure, in which I will first consider the loom structure, later referring to the fabric produced thereby, it

will be noted that I have shown my invention as applied to an ordinary Jacquard loom.

Referring more particularly to the loom illustrated in Fig. 1, it will be observed that it comprises the usual pattern cards 1, cylinder 2, griff knives 3, needles 4, and ground harness, generally designated 5, the latter including the usual lingo mechanism, generally designated 6, and including the usual mails 7, weights 8, their flexible connections 9, and box 10. Associated with this mechanism is a usual design or standard harness generally designated 11, both the ground and standard harnesses herein being operated by the same cards, etc. though obviously different sets may be used if desired. Herein also both harnesses are passed through a usual comber board 12. Operatively disposed beneath this board 12 is also, as usual in standard Jacquard looms, the body of the loom structure. The latter herein includes a horizontal warp end roll 13 from which the warp ends are drawn, and a usual horizontal fabric roll mechanism 14 on which the woven fabric is wound, the latter mechanism including a sand roll, and both these rolls herein being carried in a loom frame 15. Herein, also the warp threads or ends 16 which pass over the body of the loom structure from the roll 13, extend transversely relative to the harnesses 5 and 11 and breast beam 17, and are acted upon by the shuttle 18 and reed 19 in a usual manner, while the completed fabric is wound on the roll mechanism 14.

In my improved construction any desired warp ends or groups of warp ends are operatively connected to heddles of the standard harness 11 and certain improved warp slackener and doup mechanism hereinafter described, in such manner as to enable the selected warp ends or selected groups of warp ends to be woven independently of the other warp ends or of the other selected ends whenever or wherever desired. More specifically referring to the illustrative construction, Fig. 1, the warp ends to be acted upon by the slackeners are first passed over a usual adjustable guide roll 20, on the loom structure above the roll 13, and then under a laterally spaced guide roll 21, adjustable if desired, between the roll 20 and the ground harness 5. Also, operating between the rolls 20 and 21 upon any desired selected warp ends, herein on groups of two adjacent warp ends with each group spaced apart by four what may be called the "unselected" warp ends passing under the rolls 20,

21, are individual warp slackeners 22 having suitably formed ends 23. Herein, these ends 23 are perforated and twisted from the body of the slackener and suitably bushed as shown in Fig. 3, the two adjacent selected warp ends 24, 25 chosen for illustration herein, passing through each of these ends 23 as shown in Fig. 4. As illustrated in Fig. 1, these slackeners 22, of which there may be any desired number arranged in any desired arrangement wholly or partially across the loom, are herein in the form of relatively long upstanding rods pivotally connected on transverse axes at their lower ends as at 26, to slightly upturned angular extensions 27 on the front ends of vertically disposed and movable plate-like weight members 28 pivoted at their front ends at 28' on a transverse axis at the bottom of the loom, the pivots 28' herein being provided adjacent the points of junction of the extensions 27 to the weight members 28. As shown, these members 28 are in turn also each connected at their rear ends to a flexible connection 29 extending upward in front of the box 10 and connected at its upper end, as at 30, to a mail 31 which is in turn connected at 32 to a depending heddle connection 33 of the standard harness 11. Even more specifically, it will be noted that as shown in Fig. 2 each mail 31 is also provided with a plurality of apertures 34 between its ends whereby it is adapted to receive a doup 35. Herein each doup has a weight 36 on its lower end movable in a suitable aperture in the adjacent side of the box 10, and also has its looped end passed around the two previously mentioned selected warp threads 24, 25 which extend through the slackeners 22.

More particularly, it will be noted that the arrangement is such that, slack normally being maintained ready for release in the selected groups of warp ends by the counterbalancing of the slackeners 22, when the standard harness 11 and the doup 35 are raised, this slack is released by the elevation of the selected heddles and doups and the resultant depression of their connected slackeners, and thereupon each doup acts to pull its selected warp ends from one side of the adjacent series of unselected warp ends, herein indicated at 37, 38, 39, 40, and under and up on the other side of that series. Then the ground harness, which remains inoperative during this operation, herein for a space of five picks, is again operated to pull the warp ends back and up in the usual manner. Here it should also be particularly noted that this combination of slackeners and doups, while herein shown as used to produce a fabric having a two over four arrangement, i. e. with a series of pairs of selected warp ends pulled up on the other side of a companion group of unselected four warp ends, may if desired be used in any other arrangement, such, for example, as to produce a fabric hav-

ing one over five, three over three arrangement, or the reverse of any of the arrangements mentioned, the particular relation depending upon the particular effect desired and the material woven. For bed spreads, however, I prefer the two over four arrangement shown as this seems best adapted to give the rough, hand-crochet effect desired. Also it will be understood that the number and arrangement of slackeners and doups may similarly be varied as desired, the same being arranged in any arrangement wholly or partially across the loom as desired or required and, further, through their connection to the standard harness, being operable independently, or in any sequence, or rendered operative or inoperative as desired to produce any desired design indicated by the cards. Here it will also be noted that to guide the slackeners 22 suitable grates 41 and rollers 42 are provided for each slackener, these being disposed in the loom frame below the warp ends and above the slackener pivots 26.

In the operation of my improved construction, it will be understood that the Jacquard loom per se will operate as usual, i. e. with its usual operation of the ground harness, shuttle, reed, etc. producing a weave in correspondence with the selected design determined by the pattern cards. When, however, the pattern is constructed in such a manner, or such a separate set of cards is used for the standard harness, as to cause operation of the doup heddles and doups, (either singly, in any desired sequence, or in accordance with any variable design) the weave will be changed more particularly, the two selected warp ends 24, 25 in any slackener and doup mechanism called into operation by the cards are then carried by their doup across their adjacent warp ends 37, 38, 39, 40 in such manner as to be brought up on the opposite side, the doup drawing up in this operation the slack which the normal counterbalancing of the weight 28 has caused the slackener 22 to maintain ready for release in the selected warp ends. Thus it will be noted that, as the selected warp ends are slackened independently and as these warp ends are independently caused to be brought over with respect to their fellow warp ends acted upon by the usual ground harness, and all this is entirely responsive to the operation of the standard harness and doups and controlled by the jacquard, the effects produced, including variations of leno and close weave or one to the exclusion of the other, may be varied into any of the forms obtainable from a jacquard design.

Thus, for example, as illustrated in Fig. 5, a fabric may be produced having closely woven surrounding cross and side borders with an inner leno section in turn enclosing a closely woven section, while this latter section in turn surrounds a leno ground having

on it a closely woven design surrounding another leno center. In fact, the arrangement of leno work and closely woven work and the designs of form and figure formed with either 5 a leno or a closely woven ground is subject to almost infinite variation, and yet at the same time whenever desired a completed article, such as a spread, may be produced having the close woven side and cross borders so much 10 desired. Referring to Fig. 6, in which the weave is considerably magnified for purposes of clearness of illustration, it will be noticed that I have shown a fabric in which I have utilized a leno ground with a twill design 15 woven therein, although obviously if desired the twill may be used for the ground and the leno for the design without in any way interfering with the possible variation of the design or the creation of the desired side and 20 cross borders. Referring more particularly to this figure, it will be noted that a two over four weave is used with five threads in the weft, such a fabric being produced by the mechanism previously described and apparently best reproducing the desired hand-crochet effect at the same time that it is adapted 25 for bed spread purposes. It will be evident, however, that there may be desirable variants of this weave both as to warp and 30 weft, and that these may be produced depending upon the jacquard cards and weft selected.

Considering the weave in Fig. 6 more closely, it will also be noted that one slackener and doup mechanism, for example, causes the 35 three leno effects at the right, indicated at A, though obviously any one or all may be omitted as determined by the cards. Similarly, the next adjacent slackener and doup mechanism, which is also capable of being 40 operated independently in accordance with my invention, herein causes a separate series of leno work such as that next adjacent at the left at B, but herein note that this starts at a later point, any slackener and doup connection by my improvement being made 45 capable of starting or stopping independently of any other. Similarly, the third, fourth, fifth or any number of slackener and doup connections, each of which is capable of being 50 operated independently or rendered independently idle or inoperative whenever desired, may cooperate to cause any desired leno or ground effect at any desired point or points in the fabric, the operation of the 55 slackeners and doups, whatever the selected design of the fabric and whether a leno ground with a close woven design or a close woven ground with a leno design is used, being determined solely by the pattern cards.

60 It will, of course, be understood that the fabric is so shown in Fig. 6 as to bring out most clearly the path of the warp ends acted upon by the slackeners, and that the cooperating warp ends, shown in that figure as four warp 65 ends extending vertically through the two

deflected warp ends, in the actual fabric also pass transversely relative to these two warp ends in substantially the same manner as the two warp ends are shown to pass relative to the four in Fig. 6; thus enabling both sets 70 of warp ends to be drawn from the same roll.

As a result of my improvement it will be observed that it is made possible to produce a machine made fabric having the general appearance of hand crochet work and in 75 which the design is subject to any desired variation without necessary repetition across the fabric, or restriction to simple subjects such as have heretofore been necessary. At the same time, it will be noted that, due to 80 the large number of hooks which in my construction are left available for the design, it is made possible for this fabric to have the side and cross borders so desirable in certain products, such as bed spreads, irrespective of 85 how complex the center design may be. Attention is also directed to the fact that this improved fabric is herein obtained by the use of an entirely simple and inexpensive mechanism capable of being applied to stand- 90 ard Jacquard looms without substantial change therein, the only changes necessary for example in a Jacquard loom equipped for plain or damask work, being the provision of the inexpensive mechanisms constructed 95 in accordance with my improvement and their ready and quick insertion at small expense on the base of such a standard loom construction. It will also be observed that my slackener mechanism is exceedingly effective, 100 my improved slackeners tending to maintain the same slack at all times with a minimum of attention on the part of the weaver. More particularly, it will be noted that due to the counterbalancing of the slackeners and their 105 connection to the doup harness as herein, the strain upon the heddles is minimized. Also the slackeners are rendered readily and certainly operable by the harness and gravity, respectively, while the guides provided further assist in maintaining the desired facility and certainty of operation. At the same time, 110 it is made possible by connecting a harness and my slackeners, to reduce the length of the strings as compared with previous devices. 115 As a result, in my improved construction both the loss of slackening effect arising from stretching and the need for adjusting the strings to take up stretch are minimized. The location of this slackener mechanism beneath 120 the warp is also advantageous, permitting handy access to the slackener mechanism by the weaver if and when necessary. As a result of providing slackener mechanism so disposed, it is also made possible to facilitate 125 access of the weaver when necessary from the back of the loom, no additional strings being in the way in rear of the usual harnesses. By the provision of my improved mechanism it is also made possible to reduce the number 130

of strings required in front and back of the loom, thereby through the reduction in the strings not only reducing the cost of equipping and maintaining a loom, but further facilitating access of the operator at these points and also reducing the number of holes required in the comber board. These and other advantages of my improvement will, however, be clearly apparent to those skilled in the art.

While I have in this application specifically described one embodiment which my improved mechanism may assume, it will be understood that this is entirely an illustrative disclosure and that the mechanism may be modified without departing from my invention, it being my intention to include all such departures or modifications within the scope of the appended claims.

20. What I claim as new and desire to secure by Letters Patent is:

1. The step in leno weaving which consists in controlling from adjacent the lower end of the doup harness strings the slack in warp ends.

2. The step in leno weaving which consists in controlling from the doup mails the slack in warp ends.

30. A loom having hooks and a doup harness connected thereto, and individual warp end slackeners disposed beneath the warp and actuated by said hooks.

35. A loom having a doup harness and a comber board through which said harness is passed, and individual warp end slackeners connected to strings of said harness below the comber board.

40. A loom having doups and heddles therefor, and mechanism connected to said heddles and disposed beneath the warp for automatically inserting and removing slack in warp ends.

45. A loom having hooks and a doup harness connected thereto, and individual warp end slackeners having counterbalances connected to strings of said harness below the hooks, said counterbalances being disposed beneath the warp.

50. A loom having a doup harness and a comber board through which said harness is passed, and individual warp end slackeners connected to strings of said harness below the comber board, said slackeners being disposed beneath the warp.

55. A loom having doups including heddles therefor, and mechanism controlled by the doup mails for automatically inserting and removing slack in certain selected individual warp ends.

60. A loom having doups and heddles therefor and individual warp end slackening mechanism, and means connected to the lower ends of the doup heddles for automatically operating the slackening mechanism.

10. A loom having doups and heddles therefor and individual warp end slackening mechanism, the latter disposed beneath the warp, and means operated by the doup heddles for automatically operating the slackening mechanism.

70. 11. A loom having individual warp end slackeners and individual counterbalancing means therefor normally holding the slackeners in warp deflecting position, one of said elements being disposed beneath the warp.

12. A loom having individual warp end slackeners normally elevating the warp ends and means for individually lowering the slackeners to provide slack, both of said elements being disposed beneath the warp.

75. 13. A loom having doups and heddles therefor, and counterbalanced normally elevated individual warp end slackeners beneath the warp normally deflecting the warp ends and lowered when the heddles are raised.

80. 14. A Jacquard loom having a harness equipped for leno work and means disposed beneath the warp for inserting slack in selected warp ends in accordance with the pattern cards.

85. 15. A Jacquard loom having a harness equipped for leno work, individual warp end slackeners, and actuating means therefor connected to heddles of said harness beneath the warp and operative to insert slack in selected warp ends at any point in the design.

90. 16. A Jacquard loom having a harness equipped for leno work, slackeners operable on warp ends and disposed beneath the warp, and means controlled by heddles in said harness and likewise disposed beneath the warp for rendering any one of said slackeners operative to insert slack.

95. 17. A Jacquard loom having a harness equipped for leno work, and counterbalanced slackeners disposed beneath the warp operable upon actuation of said harness and individually controlled by the pattern cards.

100. 18. A loom having provision for inserting slack in a selected warp thread, including a slackener and an operatively connected counterbalance therefor, the latter being located beneath the warp, and slackener actuating means connected to said counterbalance.

115. 19. A Jacquard loom equipped for leno work and having operatively connected doups and slackeners connected to the heddles thereof adjacent their lower ends and acting on selected warp ends independently in accordance with the design.

120. 20. A Jacquard loom equipped for leno work and having doups and slackeners each acting on the same warp ends and each connected to heddles thereof, with the slackeners operated by the doup mails to create the slack for the doups.

125. 21. A loom having doup and slackener mechanisms including doups operating to

take up the slack inserted by the slackeners and carry up the warp ends on the opposite side of adjacent warp ends, and operative connections between the doup heddles and slackeners including slackener counterbalancing members beneath the warp.

22. An individual warp end slackener mechanism for looms comprising a slackener arm adapted to deflect a warp end and a weighted member pivotally connected thereto adapted to normally hold said slackener arm in warp deflecting position while substantially counter balanced by said slackener arm.

23. An individual warp end slackener mechanism for looms comprising an elongated arm adapted to engage and lift a warp end, a weighted member pivotally connected to said arm and supported for pivotal movement in the base of the loom normally holding said elongated arm in elevated position, and guide mechanism for the warp engaging end of said elongated arm.

24. A loom having beneath the warp a plurality of slackener arms each adapted to deflect a warp end, and a plurality of weighted members pivotally connected thereto and adapted to hold said slackener arms normally in raised warp deflecting position, said weighted members being pivotally supported on the loom beneath the warp.

25. A loom having beneath the warp a plurality of slackener arms each adapted to deflect a warp end, a plurality of weighted members pivotally connected thereto and adapted to hold said slackener arms normally in raised warp deflecting position, said weighted members being pivotally supported on the loom and likewise disposed beneath the warp, and guiding mechanism in the loom frame beneath

the warp guiding the movement of said slackener arms.

26. A loom equipped for leno work having a warp end deflecting arm, means substantially counterbalanced thereby but holding the same in warp deflecting position, and slack inserting means including a connection between the doup heddle acting on the selected warp end and said holding means.

27. A loom equipped for leno work having a warp end deflecting arm, means substantially counterbalanced thereby but holding the same in warp deflecting position, and slack inserting means including a connection between the doup mail acting on the selected warp end and said holding means, said arm and its holding means being disposed beneath the warp.

28. A loom having a heddle, a mail connected thereto, a doup operatively connected to said mail and controlling a warp thread, a slackener pivotally mounted on the loom and engageable with the warp end controlled by said doup and acting to deflect said end, and a connection between said mail and said slackener operative to move the latter about its pivot when said heddle is raised.

29. A loom having a heddle, a mail connected thereto, a doup operatively connected to said mail and controlling a warp thread, a slackener pivotally mounted on the loom and having means normally causing the same to engage the warp end controlled by said doup and acting to deflect said end, and a connection between said mail and said last mentioned means operative to move the latter about its pivot when said heddle is raised.

In testimony whereof I affix my signature.

MARTIN D. GOURLAY.
